UNITED STATES PATENT OFFICE.

FERGUS A. BUTLER, OF DANVERS, MASSACHUSETTS.

OVERCOAT.

1,214,893.

Specification of Letters Patent.

Patented Feb. 6, 1917.

Application filed April 24, 1916. Serial No. 93,251.

To all whom it may concern:

Be it known that I, FERGUS A. BUTLER, a citizen of the United States, residing at Danvers, in the county of Essex and State 5 of Massachusetts, have invented certain Improvements in Overcoats, of which the following description, in connection with the accompanying drawings, is a specification, like reference characters on the drawings indicating like parts in the single figure.

This invention relates to overcoats, ulsters, reefers and similar outside garments hereinafter, for convenience, referred to generically as overcoats, and which are designed to be worn in very cold weather. The invention has for its chief object to devise a garment of this general type which will afford the wearer greater protection against cold than do garments of this kind 20 as usually constructed.

The manner in which it is proposed to accomplish this object, and the various features of the invention, will be readily understood from the following description of 25 one embodiment thereof, reference being made to the single figure of the accompanying drawings, which shows in elevation the inside of an overcoat constructed in accordance with this invention.

The overcoat shown in the drawings is constructed in the usual manner, except that it has a short loose skirt or flap 2, secured to the inside thereof in position to encircle the body of the wearer. The upper edge of this 35 skirt is sewed, or secured, in any suitable manner to the inside of the coat from a point about where the lining begins on one side to about the point where it ends on the opposite side. This arrangement leaves two 40 free end portions *a* and *b* of the skirt, which may be fastened together at the front of the coat by means of buttons 4 on one of these end portions and corresponding buttonholes 6 provided for them in the other end portion.

The upper edges of these two end parts, *a* and *b*, are also provided with buttonholes 8 and 9 by which they may be fastened on buttons 10, secured to the inside of the coat just above the end portion *b*. 45 For the purpose of securing the lower or free edge of the skirt 2 snugly about the wearer's body this part of the skirt is hemmed to receive a draw string 12, or an equivalent fastening device. In the construction shown a very flexible belt, pro-

vided with a buckle 14, is used for this purpose.

The garment of course is put on in the usual way and the ends *a* and *b* of the skirt 2 are secured together by entering the buttons 4 in the buttonholes 6, so that the skirt entirely encircles the wearer's body. The upper edges of the end portions *a* and *b* of the skirt are then secured to the inside of the overcoat by buttoning them on the buttons 10, using the buttonholes 8 and 9 for this purpose. The draw string, or belt 12, is then pulled up and fastened, thus securing the lower, or free edges of the skirt, snugly about the wearer's body. Since the upper edge of this skirt is now secured for substantially its entire length to the inside of the overcoat while the lower edge is fastened tightly around the wearer's body, this skirt completely closes the space 75 between the body of the wearer and the overcoat, and prevents cold air from blowing up around his body to points above the skirt. It is obvious that air thus confined becomes warmed by the body very quickly; and that it will remain warm even in extremely cold and windy weather, provided some means is employed to keep this air from being displaced by cold air, or in other words, to prevent an interchange of the air around the 80 body. The skirt 2 performs this function. It is a well known fact that teamsters, rangers, woodsmen and others exposed to very severe weather find that the warmth of an overcoat is increased by wearing a belt 90 around it.

The reason undoubtedly is that just given; and the construction provided by this invention produces this effect more efficiently and at the same time affords greater 95 freedom of movement and avoids the clumsiness caused by wearing a belt around a heavy overcoat.

The skirt 2 obviously should be made of some soft fabric or other suitable material which will not permit too free a flow of air through it. The skirt may be located at any height in the coat which the wearer finds convenient; but preferably should be placed in the general region of the hips 100 and as low as it can be worn comfortably; since, obviously, the lower this barrier to the passage of cold air is placed, the greater 105 will be the protection afforded by it.

While I am aware that special linings for 110

outside garments, and other expedients resembling this invention broadly, have been proposed heretofore, the arrangements of this character with which I am familiar 5 have all proved either relatively expensive or too cumbersome to be used to any great extent. I regard the extreme simplicity of the construction herein disclosed, and the fact that it adds only a trifling cost to the 10 expense of manufacture of the garment, as important features of this invention.

Having thus described my invention, what I claim as new and desire to secure by Letters Patent of the United States is:

- 15 1. An overcoat having a short skirt constructed to encircle the wearer's body and secured at its upper edge to the inside of the coat, the other edge of said skirt being free, and means for fastening said free edge 20 snugly about the body of the wearer to close the space between his body and the inside of the overcoat.

2. An overcoat having a short skirt con-

structed to encircle the wearer's body in the region of the hips, one edge of said skirt 25 being secured to the inside of the overcoat in the region between the hips and the arm holes, and the other edge of said skirt being free, a flexible fastening means for securing said free edge of the skirt snugly about the 30 body of the wearer, said skirt having ends at the front of the overcoat, and means for fastening said ends together.

3. An overcoat having a short loose skirt constructed to encircle the wearer's body, 35 and secured at one edge to the inside of the coat, the other edge of said skirt being free, means for securing said free edge snugly about the wearer's body, said skirt having free end portions at the front of the over- 40 coat and means for fastening said portions together and to the overcoat.

In testimony whereof I have signed my name to this specification.

FERGUS A. BUTLER.
